[57] **CLAIM**

The ornamental design for a "game call", as shown and described.

DESCRIPTION

FIG. 1 is a perspective view of the game call, showing my new design;

FIG. 2 is a top elevation of the game call;

FIG. 3 is a bottom elevation thereof;

FIG. 4 is a right side elevation thereof, the left side being a mirror image thereof;

FIG. 5 is a front end elevation thereof; and,

FIG. 6 is a rear end elevation of the game call illustrated in FIGS. 1-5.
